UNITED STATES PATENT OFFICE

RAYMOND I. BASHFORD, OF PHILADELPHIA, PENNSYLVANIA, ASSIGNOR TO ATLAS POWDER COMPANY, OF WILMINGTON, DELAWARE, A CORPORATION OF DELAWARE

EXPLOSIVE CARTRIDGE AND METHOD OF MAKING THE SAME

Application filed July 20, 1932. Serial No. 623,651.

This invention relates to improvements in explosive cartridges and methods of making the same. The principal object of the invention is to provide an improved explosive cartridge by means of a novel method.

A more specific object of the invention is to provide an improved explosive cartridge comprising a powder-packed shell container having its ends closed and sealed by cup-shaped closure members which fit nicely into the ends of the container and are interlocked therewith and sealed thereto by means of a self-hardening sealing medium, such as paraffin wax.

Another object of the invention is to provide a novel method of making an improved explosive cartridge having the structural characteristics above mentioned.

Other objects and features of the invention will more clearly appear hereinafter as the description proceeds. In the drawings:

Fig. 1 is a schematic illustration of apparatus adapted to carry out the proposed method of making the improved explosive cartridge;

Fig. 2 is a detail sectional view of a part of the apparatus;

Fig. 3 is a detail sectional view taken along the line 3—3 of Fig. 2;

Figs. 4 to 6 are further detail sectional views illustrating clearly this same part of the apparatus;

Figs. 7 to 9 are detail views illustrating another part of the apparatus;

Figs. 10 to 12 are partial perspective views of the improved explosive cartridge further illustrating the proposed manner of construction; and

Fig. 13 is a detail view of still another part of the apparatus.

Referring to Fig. 1 for a general understanding of the proposed method and apparatus which may be used to perform the same, there is shown at 1 a feed hopper which is adapted to receive powder-packed, cylindrical shell containers 2 having open ends which project beyond the ends of the powder. These powder-packed shell containers are preferably formed in the manner and by means of the apparatus disclosed and claimed

in my co-pending applications, Serial No. 622,979, filed July 16, 1932, and Serial No. 622,978, filed July 16, 1932. The first of these applications discloses apparatus for advantageously packing powder in shell containers, 55 while the second discloses apparatus for evening the ends of the packed powder in each of the shell containers. While it is preferred to pack the shell containers in accordance with the teachings of these applications, it will be understood that this operation is preliminary to the method contemplated by the present invention and forms no part of this invention. Accordingly, this preliminary operation may be performed by 60 any suitable means other than that above mentioned.

Hopper 1 is adapted to feed the powder-packed shell containers onto intermittently movable conveyor 3, preferably formed of 70 leather or like material and is constructed so as to have spaced projections 5 in order to provide seating spaces 6 for individually and successively receiving the various shell containers and for spacing the containers. The 75 powder-packed shell containers carried by the conveyor pass successively through a device 7, to be described in detail hereinafter. For the purpose of the immediate general description, it suffices to state that this device functions to form cup-shaped closure members and to insert these members into the open ends of the containers. With the end closure members thus inserted, the shell containers pass along a device designated 80 generally by reference character 8 which serves to interlock the closure members with the shell containers and to seal the ends of the containers. This device will also be described in detail later. The shell containers now pass along to the end of conveyor 3 where they are dropped onto an incline 9, which, in turn, deposits them on a screen conveyor 10. This conveyor carries the containers successively through a spraying device 11, also described in detail hereinafter. In each of the operations performed by devices 8 and 11, a self-hardening sealing medium, which is preferably molten paraffin wax, is sprayed or otherwise suit- 100

ably applied to the shell containers and to this end, the apparatus, designated generally by reference character 12, is provided. After leaving device 11, the shell containers 5 are carried by conveyor 10 to an incline 13, which successively deposits them in a suitable deposit receptacle or the like.

Considering now in detail the various steps involved in the proposed method and referring 10 particularly to Figs. 2 and 6, wherein device 7 is illustrated, this device comprises a pair of spaced stationary die members 14 between which conveyor 3 moved. A pair of gripping members 15 are fixedly mounted on 15 the walls 16, which serve to support the die members. Gripping members 15 have their lower depending ends 17 formed to provide a V-shaped recess having saw-tooth gripping surfaces, as illustrated more clearly in 20 Fig. 3. These gripping members are adapted to cooperate with movable gripping members 18 which have their upwardly extending ends formed similarly to the downwardly extending ends of members 15.

25 Die members 14 each have a longitudinal bore opening 19 extending therethrough. These die members are recessed at 20 to provide an annular shoulder 21. A pair of longitudinally movable die members 22 are 30 adapted to cooperate respectively with the stationary die members 14. Each of the movable die members has a projecting punch head 23, which is shaped so as to seat nicely within recess 20 of die members 14. Slid- 35 able rods 24 extend centrally through bore openings in die members 22 and are adapted to move longitudinally with respect to the die members. Suitable guides or retainers 25 are disposed adjacent die members 14 and serve to support and guide intermittently moving webs 26 of suitable material, such as paper or thin cardboard. The mechanisms for moving the various 40 parts of this device are not shown herein 45 for the reason that the apparatus is not considered to be a part of the present invention and only the essential elements thereof which are requisite to a clear description of the method are disclosed.

50 In operation, conveyor 3 moves intermittently through device 7, as above stated, and between the die members of this device. The conveyor brings the powder-packed shell containers successively to a proper position in 55 device 7 and stops one of the shell containers being illustrated in such position in Fig. 2. At this time, the movable gripping members 18 move upward and lift the shell container bodily (see Fig. 4) until it engages the upper 60 stationary gripping members 17. The shell container is now firmly held between the respective pairs of gripping members. In this position, the container is in proper alignment with the openings 19 of die members 14, as 65 shown clearly in Fig. 5. During this opera-

tion, die members 22 move longitudinally and the punch heads 23 of these die members punch disks from the webs 26 and carry these disks into die members 14, as illustrated in Fig. 4. While the formation of only one of the disks is shown, it will be understood that the other is similarly and simultaneously formed. Die members 22 now retract slightly to release the disks and rods 24 move into openings 19 of die members 14. The movable rods engage the disks and force them through openings 19, causing the disks to become cup-shaped, as illustrated clearly in Fig. 5. Since the rods engage a central circular area of the disks and the peripheral edges thereof are free, the forcing of the disks into openings 19 causes the peripheral edges thereof to flange, as illustrated. The movable rods carry the cup-shaped members through die members 14 and into the open ends of the powder-packed shell container which has been brought into alignment with the die members, as above described. This is shown clearly in Fig. 6. The cup-shaped closure members are of such diameter as 90 to fit nicely within the ends of the shell container and are of such depth as to leave the ends of the shell container projecting beyond the peripheral flange edges of the closure members. The closure members are 95 pushed into snug engagement with the ends of the powder within the shell container, as illustrated.

Rods 24 now recede and die members 22 resume their original position. At the same time, the lower movable gripping members 18 move downward and again deposit the shell container upon conveyor 3. This container is moved along and the next one takes its place in proper position in device 7. The operation just described is repeated and the successive shell containers are thus provided with the end closure members. Each of these successive operations takes place very rapidly so that the shell container is lifted from conveyor 3, operated upon, and returned to the conveyor before it starts to move again. 100 105 110

In Figs. 7 to 9, device 8 is illustrated in detail.

This device comprises a trough 28 to which is affixed a supporting bracket 29 having upstanding recessed ends 30 which are adapted to receive and support the successive shell containers. The self-hardening sealing medium above mentioned, which is preferably molten paraffin wax, is continuously supplied to the device, via pipe 31, which has connected thereto a T-coupling 32 leading to pipes 33 which in turn carry emission nozzles 34 at their free ends. A return pipe 35 is connected to trough 28 and serves to return the unused or excess molten wax to its source, all of which will be more clearly understood hereinafter. 115 120 125

Device 8 further comprises a pair of con- 130

tinuously rotating and reciprocating die members 36 which are rotated and moved longitudinally by means of suitable apparatus (not shown). As shown clearly in 5 Figs. 8 and 9, each of these rotatable die members has a recessed head 37. The recess 38 in each of the die heads communicates with a deeper annular recess 39 in which are preferably, though not necessarily, provided 10 spaced ridges 40. These ridges have smoothly curved surfaces, as clearly illustrated. The annular recess is of such diameter that it will receive the end of the shell container. 15 As each successive shell container approaches device 8, the operator lifts it from conveyor 3 and places it upon the supporting bracket 29, as shown clearly in Fig. 7, while the die members 36 are in the retracted position shown. Die members 36 are automatically 20 moved into cooperative relation with the ends of the shell container. The spraying of molten wax serves to coat the inner surfaces of the die members and these surfaces apply the wax to the ends of the shell container. 25 As the ends of the container enter the die members, the extending portions of the ends are curled or crimped with the flanges of the closure members, as illustrated clearly in Fig. 9. It is to be remembered that die members 30 36 are continuously rotating and the spaced ridges 40 serve to effectively curl the ends in the desired fashion. In this manner, the cup-shaped closure members are interlocked with the shell container substantially simultaneously 35 with the application of the molten wax to the container ends. Although, the application of the wax and the interlocking of the cartridge elements is preferably carried out simultaneously, the interlocking or crimping 40 may be done after the application of the wax so long as the wax remains in its molten condition.

After each successive cartridge is treated in the manner above described by means of device 8, the operator places it again upon conveyor 3. The crimping and spraying operation can be performed very rapidly.

Figs. 10 and 11 illustrate the cartridge before and after the operation performed by device 8. After the cartridge leaves device 7, the ends thereof are as clearly illustrated in Fig. 10. After the curling or crimping operation is performed by device 8, the ends of the cartridges are formed as shown in 55 Fig. 11.

The cup-shaped closure members are preferably formed from solid disks of paper or thin cardboard. It is customary in using explosive cartridges in mines or like places to 60 place a plurality of them end to end so as to obtain their additive effect. A fuse is introduced part way into the last or top cartridge. When thus placed in end to end relation, the cartridges depend for their successful operation upon the ready ignition of one from

another. In other words, after the last cartridge is ignited by the fuse, the succeeding cartridges must ignite successively and quickly. Heretofore, it has been customary to use several pellets comprising a stick 70 wrapped in thin waxed or oiled paper and to fold the paper over the ends to protect the powder. This has resulted in several layers of paper which constitute a relatively thick wall or partition, and it has been necessary to puncture the folded ends to obtain the proper ignition. As is well known, mines and like places are damp, and the punctured ends of the cartridges allow moisture to enter them, thereby tending to detrimentally affect the cartridge by allowing moistening of the powder thereof. Oftimes, the powder is moistened to such an extent as to render the cartridge inoperative. The present invention eliminates entirely the necessity for puncturing the ends of the cartridges by making practical the use of thin disks to close the cartridge ends. These disks may vary in thickness but are preferably from .003 to .017 inch thick. The novel method of interlocking the disks with the shell container causes the thin disks to effectively close and seal the cartridges. Cartridges made in accordance with this invention are moisture-proof and may be used readily in mines and like places in end to end relation without puncturing. Due to the thinness of the disk closure members, these members allow rapid ignition of the successive cartridges. 80 85 90 95 100 105 110 115 120 125 130

Instead of using thin solid disks to close and seal the ends of the cartridges, thicker disks having perforations therein to render them suitable for rapid ignition may be used. Such a disk closure member is illustrated in Fig. 12. The use of thicker disks with perforations is made practical by the present invention due to the fact that the perforations are clogged with the molten wax during the making of the cartridges. The wax seals the perforation openings and makes the closure members moisture-proof. At the same time, however, the wax filling the holes does not interfere with the desired rapid ignition of the successive cartridges.

After leaving device 8, the successive cartridges pass onto conveyor 10 and into device 11. This device is illustrated more clearly in Fig. 13. It comprises a housing 42 into which pipes 43 and 44 having spray or emission openings extend. These pipes are connected to a common inlet pipe 45 which supplies molten paraffin wax to them. Housing 42 is provided with openings 46 and 47 in its opposite side walls through which conveyor 10 passes. As each cartridge passes through the housing 42, it is subjected to the spraying action of the various spray pipes from which the molten wax is emitted. Preferably, there are three sets of pipes, each set comprising those pipes clearly

shown in Fig. 13 so that the cartridge passes successively through three spray baths of the melted wax. The lower part of housing 42 is trough-shaped to receive the unused and 5 excessive molten wax which accumulates, as at 48, and the wax passes into an outlet pipe 49 connected to the trough-shaped bottom of the housing.

Referring again to Fig. 1, it will be noted 10 that the molten wax for devices 8 and 11 is supplied from a common source 50. This source may take the form of a steam heater and to this end, inlet and outlet steam pipes 51 and 52 are provided. The wax in hardened or semi-hardened condition is placed in 15 the heater and the circulating steam melts it. A common supply pipe 53 carries the molten wax to the branch pipes 31 and 45, these pipes leading respectively to devices 8 20 and 11. A suitable pump 55 is connected in the common supply pipe line 53 and serves to forcibly supply the molten wax to devices 8 and 11. The outlet pipes 35 and 49 of devices 8 and 11 respectively communicate 25 with a common return pipe 56 leading to heater 50. By means of this arrangement, the wax is kept continuously circulating and in molten form. It is, of course, apparent 30 that any other suitable arrangement for feeding the molten wax to devices 8 and 11 may be used.

After leaving device 11, the successive completed cartridges pass onto incline 13, as previously stated. It is important to note 35 that the proposed method involves several distinct steps, each of which contributes toward the making of a highly improved article. By applying a self-hardening medium to the cartridge ends simultaneously 40 with or just prior to the interlocking or crimping action, an effective sealing of the ends is had. This sealing of the ends as well as of the entire cartridge is further enhanced by the general spraying in device 11.

The method of closing an explosive cartridge as set forth herein is a decided improvement over known methods. The principal advantage is the greatly increased water resistance of the finished product. The 45 use of the cup-shaped closure members compared with the use of a plain disk is greatly advantageous when using thin members. Where the finished cartridge is sprayed with paraffin or other suitable material after the 50 closure has been made the water resistance is considerably greater than if a plain disk were used, but much greater water resistance is obtained when the cup-shaped closure members and the shell container are interlockingly 55 rolled simultaneously with the application of liquid paraffin or other suitable material.

While the novel method of the invention, as well as the improved product resulting therefrom, has been disclosed herein in a preferred form, it will be understood that various changes and modifications may be

made, especially as to details. The method may be performed by hand or by any suitable apparatus other than that disclosed herein so long as the essential steps of the method are carried out. The invention is to be limited then only by the scope of the appended claims.

I claim:

1. A method of making an explosive cartridge, which comprises packing explosive powder in a shell container having at least one open end so that the open end extends beyond the powder, placing a thin cup-shaped closure member in the open end of said container so that the peripheral wall of said member and the extending end of said container are juxtaposed, and applying to said wall and said end a self-hardening sealing medium in unhardened state and simultaneously interlocking said wall and said end. 75

2. A method of making an explosive cartridge, which comprises packing explosive powder in a shell container having at least one open end so that the open end extends beyond the powder, forming a thin cup-shaped closure member of such diameter and depth that it will fit in the end of said container and the extending end of said container will extend beyond the peripheral wall of said member, placing said member in the open end of said container against said powder, and applying to said wall and said end a self-hardening sealing medium in unhardened state and simultaneously interlocking said wall and said end. 80

3. A method of making an explosive cartridge, which comprises packing explosive powder in a shell container having at least one open end so that the open end extends beyond the powder, forming a thin cup-shaped closure member of such diameter and depth that it will fit in the end of said container and the extending end of said container will extend beyond the peripheral wall of said member, placing said member in the open end of said container against said powder, and applying to said wall and said end a sealing medium in unhardened state and simultaneously rolling said wall and said end into interlocking relation. 85

4. A method of making an explosive cartridge, which comprises packing explosive powder in a shell container having at least one open end so that the open end extends beyond the powder, forming a thin cup-shaped closure member of such diameter and depth that it will fit in the end of said container and the extending end of said container will extend beyond the peripheral wall of said member, placing said member in the open end of said container against said powder, applying to said wall and said end a sealing medium in unhardened state and simultaneously rolling said wall and said end into interlocking relation, and applying to the com- 90

pleted cartridge a sealing medium in unhardened state.

5. A method of making explosive cartridges, which comprises packing explosive powder in a plurality of shell containers having open ends so that the open ends extend beyond the powder, successively punching thin cup-shaped closure members from moving webs, said members being of such 10 diameter and depth as to fit in the ends of said containers with the extending ends of said containers projecting beyond the peripheral walls of said members, inserting the successively formed members in the ends of 15 successive containers against the powder therein, and applying a self-hardening sealing medium in unhardened state to the peripheral walls and ends of the successively associated members and containers and simultaneously 20 interlocking said walls and ends.

6. A method of making explosive cartridges, which comprises packing explosive powder in a plurality of shell containers having open ends so that the open ends extend beyond the powder, successively punching thin cup-shaped closure members from moving webs, said members being of such diameter and depth as to fit in the ends of 25 said containers with the extending ends of said containers projecting beyond the peripheral walls of said members, inserting the successively formed members in the ends of successive containers against the powder 30 therein, applying a self-hardening sealing medium in unhardened state to the peripheral walls and ends of the successively associated members and containers and simultaneously 35 interlocking said walls and ends, and applying a self-hardening sealing medium in unhardened state to the successively completed 40 cartridges.

7. A method of making an explosive cartridge, which comprises packing explosive powder in a shell container having at least 45 one open end so that the open end extends beyond the powder, placing a cup-shaped closure member capable of rapid ignition transfer in the open end of said container so that the peripheral wall of said member 50 and the extending end of said container are juxtaposed, and applying to said wall and said end a sealing medium in unhardened state and simultaneously interlocking said wall and said end.

55 RAYMOND I. BASHFORD.
